W. A. MATZ

DUST REMOVER

Filed July 31, 1923

Patented July 8, 1924.

1,500,955

UNITED STATES PATENT OFFICE.

WILLIAM A. MATZ, OF CLINTON, IOWA.

DUST REMOVER.

Application filed July 31, 1923. Serial No. 654,909.

To all whom it may concern:

Be it known that I, WILLIAM A. MATZ, a citizen of the United States, residing at Clinton, in the county of Clinton and State of Iowa, have invented certain new and useful Improvements in Dust Removers, of which the following is a specification.

The object of this invention is to provide an inexpensive device which may be connected with any heating furnace and by the use of which the dust arising from ashes when the same are removed from the furnace and deposited in an ash can or other receptacle may be carried off through the chimney and prevented from rising through the house or other building or settling upon objects stored in the cellar in which the furnace is set up. The invention seeks to provide a device for the stated purpose which will not interfere in any way with the operation or efficiency of the furnace and which may be very quickly and easily adjusted for use when the ashes are to be removed. The invention is illustrated in the accompanying drawing and will be hereinafter fully set forth.

In the drawing:

Figure 1 is an elevation of a furnace having my dust-removing attachment applied thereto, and

Fig. 2 is an enlarged vertical section through the attachment and the adjacent portion of the furnace.

The furnace 1 may be of any well-known type and is illustrated as a hot-air furnace having an outer casing 2 connected by flues 3 with the various rooms of the building, and also equipped with a smoke flue 4 establishing draft through the fire-box 5 and the chimney. In carrying out my invention, I provide an opening 6 in the wall of the fire-box, and to the outer side of the furnace I secure a sleeve or tube 7 which extends from the fire-box through the casing 2 and has the end edges of its side walls inclined downwardly and outwardly, as shown at 8. To the upper side of this sleeve 7, I hinge a door 9 which will ordinarily be held in closed position by gravity so as to rest upon the inclined edges 8 and positively shut off circulation of air through the tube, as will be readily understood. I also secure to the casing 2 a housing 10 which may have its vertical wall in arcuate form concentric with the casing or may be of angular design as preferred. The upper portion of this

casing constitutes a hood 11 which fits around the sides and the top of the flue or sleeve 7 so as to entirely house the same and the door or closure 9 therefor, the front of the housing below the hood being open, as shown at 12. In the top of the hood is an opening 13, and pivoted to the closure 9 near the lower edge thereof is a rack bar 14 extending through the said opening 13 and constituting a handle by which the door may be manipulated. The teeth or lugs 15 of this rack bar are adapted to engage the top of the hood at one edge of the opening 13, as shown clearly in Fig. 2, so as to support the closure in its opened position.

When the ashes are to be moved, the usual fuel door 16 of the furnace and the damper therein are closed and the damper in the smoke flue 4 is opened. The ash pit door 17 is, of course, opened so as to permit access to the ashes and a strong draft will thus be created through the furnace and the flue 4, as will be readily understood. The ash can or other receptacle 18 is placed upon the housing 10 through the open front side thereof and the closure 9 is opened, as shown in Fig. 2. As a result of this arrangement, a strong draft through the sleeve or tube 7 will be set up so that, when the ashes are dumped into the can 18, the dust arising therefrom will be drawn through the sleeve 7 into the fire-box of the furnace and thence out through the flue 4 and will be carried out through the chimney 90 instead of flying about the cellar and settling on objects therein and rising through the house to the damage of furniture and drapery. My device is exceedingly simple in construction and may be readily applied 95 to any furnace. When it is not to be used, the closure 9 is permitted to drop so as to cut-off circulation through the sleeve 7 and the draft through the furnace is then regulated in the usual manner. The device takes 100 up very little room in the cellar and does not necessitate any very substantial alteration or reconstruction of the furnace, it being necessary merely to form openings to accommodate the sleeve 7 and then secure 105 the sleeve in place so that it will fit tightly to or through the said openings.

Having thus described the invention, what is claimed as new is:

The combination with a furnace having 110 an opening in its side establishing communication with the fire-box of the furnace

at a point removed from the fuel door, of a tube enclosing and extending laterally from said opening, a closure hinged at the upper edge of the outer end of said tube and adapted to entirely cover the outer end of the tube, a housing secured to the side of the furnace and including an upper hood completely housing said tube and the closure therefor and having an open bottom below the tube, the lower portion of said housing extending from the lower edge of

the hood to the floor upon which the furnace rests and having its front side open to admit a receptacle, and a rack bar pivoted to said closure and extending therefrom through the top of the hood and engageable with the top of the hood to support the closure in open position.

In testimony whereof I affix my signature.

WILLIAM A. MATZ. [L.S.]
